DESIGN FOR A BLOUSE

Violet Giovagnoni, New York, N. Y.

Application February 1, 1947, Serial No. 136,614

Term of patent 3½ years

(Cl. D3—25)

To all whom it may concern:

Be it known that I, Violet Giovagnoni, a citizen of the United States, residing in New York city, in the county of New York and State of New York, have invented a new, original, and ornamental Design for a Blouse, of which the following is a specification, reference being had to the accompanying drawing, forming part thereof.

Fig. 1 is a front view of a blouse showing my design,

Fig. 2 is a rear view thereof, and

Fig. 3 is an enlarged fragmentary view of the blouse shown in Fig. 1 illustrating the trim detail of the blouse.

I claim:

The ornamental design for a blouse, substantially as shown.

VIOLET GIOVAGNONI.
